CLAIM

We claim the ornamental design for a digital audio disk player, as shown and described.

DESCRIPTION

FIG. 1 is a top perspective view of a first embodiment of a digital audio disk player of the present invention;

FIG. 2 is a front view thereof;

FIG. 3 is a first side view thereof;

FIG. 4 is a top view thereof;

FIG. 5 is a second side view thereof;

FIG. 6 is a rear view thereof;

FIG. 7 is a bottom view thereof;

FIG. 8 is a top perspective view of a second embodiment of a digital audio disk player of the present invention;

FIG. 9 is a front view thereof;

FIG. 10 is a first side view thereof;

FIG. 11 is a top view thereof;

FIG. 12 is a second side view thereof;

FIG. 13 is a rear view thereof; and,

FIG. 14 is a bottom view thereof.

The ornamental design which is claimed is shown in solid lines in the drawings. Any broken lines in the drawings are for illustrative purposes only and form no part of the claimed design.
